ELECTRIC SWITCH

Alfred G. von Normann, Seattle, Wash., assignor
to Trumbull Electric Manufacturing Company,
Pacific Division, Seattle, Wash., a corporation
of Washington

Application March 22, 1933, Serial No. 662,010

9 Claims. (Cl. 200—50)

My invention relates to an electric switch and the general object of my invention is to provide an electric switch which is simple in construction; reliable, efficient and safe in operation; not expensive to manufacture; easy to install and service and safe to handle, due to the provision of safety features embodied in the construction of the switch and the housing or receptacle for said switch.

10 Another object of the invention is to provide an electric safety switch having a switch plate slidably positioned between two sets of terminals, said switch plate comprising a piece of insulating material having electrically conductive inserts 15 therein, the inserts being movable into and out of electrical contact with the terminals, the insulating portion of the plate remaining between the terminals when the switch is in "open" position.

20 Another object is to provide an electric switch in which the circuit through a pair of terminals is always broken at two points or locations instead of at one point when the switch is moved from closed to open position thereby reducing 25 arcing and the destructive effects incident thereto.

Another object is to provide an electric safety switch of very compact construction, the provision of a plate of insulating material between the 30 terminals making it possible to place these terminals very close together without danger of short circuiting when the switch is in open position.

Other objects are to provide an electric safety 35 switch and cabinet box therefor embodying improved means for operating the switch, together with improved means which automatically locks said switch operating means in an open circuit position when the cover of the switch cabinet is open and which automatically locks said cover in a closed position when the switch is electrically 40 closed, the said safety locking means making it necessary to move the switch to open circuit position before the cover of the cabinet box can be 45 opened and further making it impossible to move the switch to closed circuit position while the cover of the cabinet box remains open.

Other and more specific objects of the invention will be apparent from the following description taken in connection with the accompanying drawings.

In the accompanying drawings Fig. 1 is a longitudinal sectional view substantially in a medial plane, of a safety switch and cabinet box therefor 55 constructed in accordance with my invention,

the switch being shown in closed circuit position.

Fig. 2 is a plan view of the same switch as it might appear if the entire cover were removed from the cabinet box.

Fig. 3 is sectional view similar to Fig. 1 except that the switch is shown in open circuit position.

Fig. 4 is a detached plan view of a sliding switch plate forming a part of my invention.

Fig. 5 is a sectional view of said switch plate taken substantially on broken line 5—5 of Fig. 4. 10

Fig. 6 is a fragmentary detached view in elevation, with parts shown in section substantially on broken line 6—6 of Fig. 3, of a switch lever and locking mechanism constructed in accordance 15 with my invention.

Fig. 7 is a fragmentary side elevation with parts shown in section of the mechanism illustrated in Fig. 6.

Figs. 8 and 9 are detached perspective views 20 respectively of two switch terminal clips embodied in the invention.

Like reference numerals designate like parts throughout the several views.

Referring to the drawings: 10 designates a block or frame of insulating material which may 25 be disposed within a receptacle or switch box 11. Foot portions 12 on the block 10 may rest upon a thin insulation plate 13 which is supported on raised portions 14 in the bottom of the housing 10. Screws 15 secure the block 10 and insulation 30 plate 13 to the raised portions 14.

The block 10 is recessed on its bottom side as at 16 for the reception of two sets of switch terminals 17 and 18 between which a slidible 35 switch plate, designated generally at 20, is operatively disposed. The switch shown in the drawings is constructed for a three wire circuit, consequently three each of the terminals 17 and 18 are used. Each terminal 17 embodies a U shaped portion having a shorter leg resting 40 against the block and connected by a screw 21 with a fuse bracket 22 and a longer leg projecting beyond the shorter leg and having a contact member 23 on the end thereof. The terminals 18 each have their outer ends positioned on the top 45 of the block 10, thence extend into the recess 16 through openings in the block 10 and are offset downwardly and terminate in a contact member 24 which is positioned in spaced relation directly 50 above and opposite to one of the contact members 23. Screws 25 secure the terminals 18 to the base block 10 and at the same time furnish means by which circuit wire holding clips 26 may be 55 electrically connected with the terminals 18.

The switch plate 20, Figs. 1, 3, 4 and 5, is pref-

erably formed of a flat plate 27 of insulating material having three metal contactors or switch blades 28, 29 and 30 of the same thickness as the insulating plate 27 inserted in suitable holes 5 in said plate 27, in relatively insulated relation, the surfaces of the blades 28, 29 and 30 being flush with the surfaces of the plate 27. Holding members 31 of insulating material are provided on opposite sides of the plate 27 in overlapped relation as respects the ends of the blades 28, 29 and 30 whereby displacement of said blades 28, 29 and 30 will be prevented. Rivets 32 may be used to secure the holding members 31 to the plate 27. These holding members 31 overlap the ends of the blade members 28, 29 and 30 whereby the holding members are clear of the terminals 17 and 18 at all times and whereby a portion of each blade member 28, 29 and 30 is left exposed for contact with said terminals 17 and 18. Relatively flat finger members 33 on the front end of the switch plate 27 are slidably disposed between the contact members 23 and 24 and occupy a position between said contact members when the switch is in the open circuit position shown in Fig. 3, thus insuring that the contact members 23 and 24 will always be held apart and kept relatively insulated when the switch is in open circuit position.

At the rear end the insulating plate 27 is provided with two slots 34 for the reception of the lower ends of a forked switch operating lever 35. This lever 35 extends upwardly through a hole 36 in a disc like portion 37 of a bracket member. The disc like portion 37 is supported by an upright portion 38 which is secured to a raised portion 40 on the base 10. Ears 41 extend downwardly from the disc 27 and the operating lever 35 is pivotally supported from said ears by a pivot 42. A finger piece 43, preferably of insulating material, is secured to the lever 35 as by screws 44 and extends above the disc 37. A curved element 45 is formed or otherwise provided on the finger piece 43 or on the lever 35 just below the disc 37 and extends forwardly and rearwardly from said lever. At the front side of the lever 35 the word "on" is inscribed on the element 45 and at the rear side of the lever 35 the word "off" is inscribed on said element 45. When the switch is closed, see Figs. 1 and 2 the word "on" will be visible through the opening 36 but the word "off" will not be visible and conversely when the switch is closed the word "off" will be visible and the word "on" will not be visible. This makes it possible to tell at a glance whether the switch is open or closed.

The fuse clips 22 are connected by fuse members 46 with other fuse clips 47 which may be connected by bus bars 48 and clips 49 with circuit wires 50.

The receptacle 11 has a cover 51 hinged thereto as by hinge means 52. This cover has an opening 53 in registration with the disc 37. The opening 53 is adapted to receive therein the raised central portion of said disc 37 in such a manner that the depressed peripheral portion of the disc 37 extends under the marginal portion of the cover around the opening 53. In connection with this cover safety means are provided for preventing the opening of the cover when the switch is closed and for preventing the switch being moved from open to closed position when the cover is open. These safety means are in the nature of an L-shaped locking arm 54 slotted as at 55 to fit over a shoulder 39 on the lever 35 whereby the locking arm 54 is pivotally connected with the said switch operating lever 35. This locking arm 54

extends forwardly from said lever 35 through a slot 57 in the upright bracket member 38. A notch 56 is provided in the upper edge of the locking arm 54 for engagement with a catch 58 which is formed by a part of the bracket 38. A compression spring 59 is positioned below the locking arm 54 and exerts an upward pressure thereon. When the switch lever 35 is in the open position the notch 56 is positioned in registration with the catch 58 and will engage with said catch 58 and lock the switch lever against movement unless downward pressure is exerted on the locking arm 54. When the cover 51 is closed the locking arm 54 will be engaged and depressed by a foot piece 60 on an angle bracket 61 which is secured to the cover 51. The downwardly protruding portion of the angle bracket 61 has a slot 62 into which the locking arm 54 may enter to thereby lock the cover 51 in the closed position. When the switch is open the locking arm 54 will be withdrawn clear of the angle bracket 61 as shown in Fig. 7, thus allowing the cover 51 to be opened. When the switch is closed the locking arm 54 will be projected forwardly through the slot 62 in the bracket 61 thus locking the cover 51 in closed position. If the cover 51 is raised while the switch is open the pressure of the foot 60 on the locking arm 54 will be released and the spring 59 will raise the locking arm so that the notch 56 will engage the catch member 58, thus making it impossible to close the switch until the cover 51 is properly closed. These safety features thus preclude access to the dangerous parts of the switch except when said switch is in open position and the circuit or circuits therethrough are broken.

In the installation of this switch the "line" wires leading from the source of energy are connected with one set of terminals as the terminals 18 and the "load" wires leading to the locations where the energy is to be delivered may be connected with the other set of terminals as terminals 17, whereby when the switch is closed current from the line wires will flow through terminals 18 and 17 thence through the fuse members 46 to load wires 50.

In the operation of this switch, when the lever 35 is in the position shown in Figs. 1 and 2 the blade members 28, 29 and 30 will be between the contact elements 23 and 24 of terminals 17 and 18 and the circuit or circuits will be closed. When the switch lever 35 is in this closed position the locking arm 54 will be projected or extended through the slot 62 and the cover 51 will be locked in a closed position. When the switch lever 35 is moved to the position shown in Fig. 3 the blade members 28, 29 and 30 will be withdrawn from contact with the contact members 23 and 24 and the circuits will be opened. When the lever 35 is thus moved to the open circuit position the locking arm 54 will release the cover. If the cover is then opened the locking arm 54 will be permitted to engage the lug 58 and the switch can not again be closed until after the cover has been closed and the locking lever 54 released from engagement with the catch member 58. When the switch plate is moved to open circuit position the circuit between each blade 28, 29 and 30 and the engaging terminals is broken at two points namely, between one side of the blade and the coacting terminal 17 and between the other side of the blade and the coacting terminal 18. This reduces arcing and lessens the damage incident thereto.

This switch is simple in construction, reliable

and efficient in operation, easy to install, not expensive to manufacture and safe to handle.

The foregoing description and accompanying drawings clearly disclose a preferred embodiment 5 of my invention but it will be understood that this disclosure is merely illustrative and that such changes in the invention may be made as are fairly within the scope and spirit of the following claims.

10 I claim:

1. In a switch of the class described, a base of insulating material, having a recess therein and having a portion overhanging said recess, two oppositely positioned contact members disposed in said recess under said overhanging portion, a switch plate of insulating material disposed within said recess in said base and positioned substantially parallel to the plane of the base and slidably movable between said two contact members, an insulating plate under said base, and a blade element of electrically conductive material in the portion of said switch plate which is movable between said contact members.

2. In a switch of the class described, a base of insulating material, having a recess therein and having a portion overhanging said recess, two oppositely positioned contact members extending into said recess under said overhanging portion, a switch plate of insulating material disposed within said recess in said base and positioned substantially parallel to the plane of the base and slidably movable between said two contact members, an insulating plate under said base, a blade element of electrically conductive material in the portion of said switch plate which is movable between said contact members and a switch operating lever connected with said switch plate, said base having an opening at one end of said overhanging portion through which said lever extends.

3. In a switch of the class described, a receptacle, a switch base of insulating material in said receptacle and having a recess formed therein and having a portion overhanging said recess, a terminal positioned in said recess under said overhanging portion and having a contact member thereon, fuse means positioned on the exterior of said overhanging portion opposite said terminal, screw means extending through said overhanging portion electrically connecting said fuse means and said terminal, another terminal secured to said switch block and extending into said recess and having a contact member thereon positioned directly opposite said first named contact member, a switch plate of insulating material disposed within said recess in said base and positioned substantially parallel to the plane of the base and slidably between said two contact members, said switch plate having a cut away portion, an electrically conductive blade element positioned in said cut away portion of said switch plate in the part which is movable between said contact members and a switch operating lever connected with said switch plate and extending to the exterior of said receptacle.

4. In a switch of the class described, a receptacle, a switch base of insulating material mounted in the bottom portion of said receptacle and having a recess formed therein and having a portion overhanging said recess, a plurality of terminals positioned in said recess under said overhanging portion and each having a contact member thereon, a fuse means positioned on the exterior of said overhanging portion opposite each of said terminals and electrically connected

with its respective terminal, a plurality of other terminals secured to the front side of said switch block and extending into said recess and each having a contact member on the end thereof positioned in close proximity to one of said first named contact members, a switch plate of insulating material disposed within said recess in said base and positioned substantially parallel to the plane of the base and slidably between said two sets of contact members, said switch plate having cut away portions, electrically conductive blade elements in said cut away portion of said switch plate and movable into and out of contact with said contact members, and a switch operating lever connected with said switch plate and extending to the exterior of said receptacle said switch base having an opening at one end of said overhanging portion through which said lever extends.

5. In a switch of the class described, a receptacle, a switch base of insulating material mounted in the bottom portion of said receptacle and having a recess formed therein, a plurality of terminals positioned in said recess and each having a contact member thereon, a plurality of other terminals secured to the upper side of said switch block and extending into said recess and each having a contact member on the end thereof positioned in close proximity to one of said first named contact members, a switch plate of insulating material slidable between said two sets of contact members, said switch plate having cut away portions, electrically conductive blade elements in said cut away portion of said switch plate and movable into and out of contact with said contact members, blade holding members positioned on opposite sides of said switch plate overlapping the edges of said blade elements, said holding members being spaced apart and operating between said contact members, a switch operating lever connected with said switch plate and extending to a point outside of said receptacle, a bracket on said switch base, and a pivot for said switch operating lever supported by said bracket.

6. In a switch of the class described, a receptacle having a cover hinged thereon for opening and closing movement, said cover having an opening therein, a switch base of insulating material mounted in the lower portion of said receptacle and having a recess formed therein, a plurality of terminals positioned in said recess, each of said terminals having a contact member thereon, a plurality of other terminals secured to said base and each having a contact member positioned adjacent a contact member of said first mentioned set of terminals, a switch plate of insulating material slidable between said contact members, switch blade inserts of electrically conductive material provided in said switch plate in the paths of contact of said switch plate with said contact members, a bracket secured to said switch base and extending upwardly therefrom and having a portion positioned within the opening in said cover, a switch operating lever pivoted on said bracket and extending outwardly through said cover and connected with said switch plate, locking means for said lever and means on said cover positioned to engage with said locking means when the cover is fully closed and move said locking means into unlocked position.

7. In a switch of the class described, a receptacle having a cover hinged thereon for opening and closing movement, said cover having an

opening therein, switch terminals disposed in said receptacle and affording spaced apart contact members, a switch plate of insulating material slideable between said contact members and having electrically conductive inserts therein movable into and out of contact with said contact members, a bracket supported in said receptacle, a disc portion on said bracket positioned in registration with the opening in said cover, a switch operating lever connected with said switch plate and fulcrumed just below said disc and extending upwardly through said disc, a locking member connected with said switch operating lever, a catch member adapted to be engaged by said locking member when the switch is in open circuit position, means on said cover adapted to release said locking member from said catch member when the cover is closed, and means on the cover engaged by the locking member when the switch lever is in closed circuit position whereby said cover will be locked closed.

8. In a switch of the class described, a receptacle having a cover hinged thereon for opening and closing movement, said cover having an opening therein, a switch base of insulating material mounted in the lower portion of said receptacle and having a recess formed therein, a plurality of terminals positioned in said recess, each of said terminals having a contact member thereon, a plurality of other terminals, secured to said base and each having a contact member positioned adjacent a contact member of said first mentioned set of terminals, a switch plate of insulating material slideable between said contact

members, switch blade inserts of electrically conductive material provided in said switch plate in the path of contact of said switch plate with said contact members, a bracket secured to said switch base and extending upwardly therefrom, a disc portion on said bracket positioned in registration with the opening in said cover, a switch operating lever connected with said switch plate and pivoted on said disc and extending above said cover, a locking member on said switch operating lever, a catch member positioned for engagement by means on said locking member when the switch is in open circuit position, means on said cover adapted to engage said locking member and hold said locking member in released position relative to said catch when the cover is closed and means on the cover engaged by the locking member when the switch lever is in closed circuit position whereby said cover will be locked closed.

9. In a switch of the class described, a plurality of electrically separated terminals, a switch plate embodying a flat piece of insulating material slideable between said terminals and having an opening therein, an insert of electrically conductive material in said opening flush with the surfaces of said piece of insulating material, and holding members positioned on opposite sides of said plate of insulating material and secured thereto and overlapping the edges of said electrically conductive insert whereby said insert is retained in place in said opening.

ALFRED G. VON NORMANN.
